UNITED STATES PATENT OFFICE.

THEODORE C. RIEBE, OF CHICAGO, ILLINOIS, ASSIGNOR TO ROGERS MOTOR LOCK COMPANY, OF CHICAGO, ILLINOIS, A CORPORATION OF ILLINOIS.

AUTOMOBILE-LOCK.

1,276,116.

Specification of Letters Patent. Patented Aug. 20, 1918.

Application filed June 13, 1917. Serial No. 174,466.

To all whom it may concern:

Be it known that I, THEODORE C. RIEBE, a citizen of the United States, and resident of Chicago, in the county of Cook and State 5 of Illinois, have invented certain new and useful Improvements in Automobile-Locks, of which the following is a specification.

My invention relates to locking devices for automobiles and particularly to an improvement 10 on the lock shown in the patent to William P. Conley, No. 1,181,571, dated May 2, 1916, Patent No. 1,238,945 to Rogers & Riebe dated Sept. 4, 1917, and co-pending application Ser. No. 174,468, filed of even 15 date herewith.

An object in the present construction is to provide a lock which shall be impregnable to attack and the operation of which is not affected by the rotation of the flexible connection 20 between the lock and the valve. To secure the desired result it has been found desirable to operate the valve by a member which is pushed and pulled as distinguished from a rotatable member. In the present instance I employ a stiff wire located at the 25 axis of a novel armored conductor, the valve being operated by a longitudinal thrust applied to the wire. To accomplish this result the rotary movement of the locking element must be changed to a reciprocating movement 30 and certain novel means are employed for accomplishing this result. Fundamentally, however, the invention contemplates the employment in connection with a rotary lock of a longitudinally, 35 slideable valve operating member, the operating member being in the form of a wire and being closely confined at the axis of a flexible conductor. This conductor is composed of a plurality 40 of independent ball and socket elements.

The invention will be more readily understood by reference to the accompanying drawings, wherein,

Figure 1 is a face view of a lock constructed in accordance with my invention;

Fig. 2 is a side elevation thereof;

Fig. 3 is a sectional view on the line 3—3 of Fig. 1;

Fig. 4 is a sectional view on the line 4—4 of Fig. 3;

Fig. 5 is a sectional view on the line 5—5 of Fig. 3, and,

Fig. 6 is a sectional view on the line 6—6 of Fig. 3.

55 In the drawings it will be seen that the

locking device is inclosed within a casing 10, the casing being suitably held in an opening in the dash 11, of an automobile. A screw-cap 12, is fitted to the open end of the casing and serves to confine the operating 60 parts therein when the lock is in unlocked position. The connection between the lock and the valve (not shown) is by means of a stiff wire 13, which is inclosed within an armored cable. The cable is composed of 65 sections, each section comprising a ball 14, and a socket 15. A longitudinal axial opening through the element is provided for the wire. Sufficient clearance is provided between adjacent sections to permit of the 70 necessary flexibility of the conductor, this being accomplished without binding the inclosed wire.

The ball 14, of the extreme section is accommodated within the socket end of a cylinder 16, welded within the opening in the end wall of the casing 10. The end of the wire is formed into a hook 17, which engages a plug 18, accommodated within the hollow end of a bolt 19. After the plug 18, is inserted, a washer 20, having an axial opening 21 considerably larger than the wire is inserted and the end of the bolt crimped thereover. By this means a swivel connection is made between the wire and the non-rotatable bolt. Inasmuch as the sections of the conductor permit swiveling and the wire is rotatably connected to the lock, it will be seen that the parts cannot be disarranged 85 by any relative rotation.

The bolt 19, is threaded into a U-shaped member 22, and further secured by a nut 23. The legs of the U-shaped member or yoke 22, engage with pins 24, 25, which project from the sides of the gears 26, 27, these gears being mounted on pivots fixed to an inner frame member 28. The apertures 29, in the legs of the member 22, for engagement with the pins 24, 25, are in the form of slots, as best shown in Fig. 4. The gears 26, 27, engage with a gear 30, which is secured to the barrel 31, of a lock by screws 32, and pins 33, as best shown in Fig. 5. The teeth of the gear 30, are formed by punching apertures 34, near the periphery of the disk composing the gear, two diametrically opposite teeth, however, being formed by the notches 35, as best shown in Fig. 6. These notches engage with lugs 36, integral with the member 28, when the parts are in unlocked position. 110

At other times the lugs 36, lie in front of the gear, as best shown in Fig. 6. This prevents separation of the lock from its coöperating parts except when in unlocked position. When the wire is disconnected at its lower end and the fastening ring 12, is removed from the casing, if the lock is moved to unlocked position, the entire lock may be moved out of the casing. This makes the operation of assembling comparatively simple.

One of the important features is the method employed for securing a reciprocatory motion in right lines without the possibility of binding. The gear attached to the lock barrel engages the peripheries of the right angularly disposed gears 26, 27, rotating the same in opposite directions. The slots 29, in the yoke permit the pins 20 which engage therewith to move in opposite directions without interfering with the right line movement of the yoke. This gives rise to another advantage. It will be seen that when the yoke is in either of its extreme 25 positions, a thrust exerted on the wire, as when attempting to cut the cable, will be exerted in line with the axis of the gears and will be ineffective toward rotating the gears. This is essential in connection with a further 30 locking provision which forms the subject matter of a co-pending application, it being essential in connection with that feature that the wire shall not be subject to elongation.

Obviously the construction is capable of 35 much modification and the desired result may be secured by the use of other mechanisms than here disclosed. I do not wish to be limited other than as indicated in the appended claims.

40 I claim:

1. In a locking device, the combination of a casing, a conduit connected thereto, a wire in said conduit, a rotatable locking element, a pair of gears located in a plane transverse 45 to the arc of rotation of the locking element, and means operable by the gears for reciprocating said wire, substantially as described.

2. In an automobile lock, the combination of a casing, a conduit connected thereto, a wire in said conduit, a gear operated by said lock, a pair of gears meshing with said first mentioned gear and mounted on pivots transverse to the pivot of said first gear, and means operable by said pair of gears for reciprocating said wire, substantially as described.

3. In a locking device for automobiles, the combination of a frame, a rotatable lock

mounted in the open end of said frame, a gear secured to the inner end of said lock, the 60 teeth of said gear being in the form of apertures located near the periphery of the gear, one of the apertures being in the form of a notch in the periphery, and a lock on the frame, said lock being so positioned as to 65 register with said notch only when the lock is in unlocked position, substantially as described.

4. In combination, a casing, a conduit connected thereto, a wire in said conduit, a 70 frame in the casing, a lock interlocked with said frame, a toothed disk secured to the lock, a pair of gears secured to the frame and meshing with the teeth of said disk, and means for connecting the wire to said gears 75 whereby the rotary motion of the lock is changed to reciprocating motion of the wire, substantially as described.

5. In a locking device, the combination of a casing, a conduit connected thereto, a wire 80 in said conduit, a lock in the casing, means operable by the lock for causing a reciprocating motion of said wire, and a swivel connection between the lock and said wire for permitting rotation of the wire on its longitudinal axis, substantially as described.

6. In a locking device, the combination of a casing, a lock therein, a valve-operating wire, and means operable by said lock for changing the rotary motion of the lock into 90 a reciprocating motion of the wire in line with the longitudinal axis of the lock, substantially as described.

7. In a device of the class described, the combination of a lock having a barrel, a 95 valve-operating wire, and means operable by the rotation of the lock barrel for changing the rotary movement of the barrel into longitudinal movement of the wire in line with the longitudinal axis of the barrel, substantially as described.

8. In a device of the class described, the combination of a lock barrel, a stiff wire adapted to be operated thereby, means for changing the rotary movement of the barrel 105 into positive, longitudinal, reciprocating movement of the wire in line with the longitudinal axis of the barrel, and means in the connection between the wire and the lock permitting rotation of the wire on its longitudinal axis, substantially as described.

Signed at Chicago, Ill., this 9th day of June, 1917.

THEODORE C. RIEBE.
